(57) **CLAIM**

We claim the ornamental design for a communications earpiece with a boom, as shown and described.

DESCRIPTION

FIG. 1 is a perspective view of a communications earpiece with a boom according to the invention;

FIG. 2 is a front view of the communications earpiece shown in FIG. 1;

FIG. 3 is a left side view of the communications earpiece shown in FIG. 1;

FIG. 4 is a rear view of the communications earpiece shown in FIG. 1;

FIG. 5 is a right side view of the communications earpiece shown in FIG. 1;

FIG. 6 is top view of the communications earpiece shown in FIG. 1; and,

FIG. 7 is bottom view of the communications earpiece shown in FIG. 1.
